I. M. YOUNGBERG

FIRELESS BROODER

Filed Nov. 16, 1922

Inventor
Ida M. Youngberg.

By Grace C. Madole

Attorney

UNITED STATES PATENT OFFICE.

IDA M. YOUNGBERG, OF GOTHENBURG, NEBRASKA.

FIRELESS BROODER.

Application filed November 16, 1922. Serial No. 601,353.

To all whom it may concern:

Be it known that I, IDA M. YOUNGBERG, a citizen of the United States, residing at Gothenburg, in the county of Dawson, 5 State of Nebraska, have invented certain new and useful Improvements in Fireless Brooders; and I do hereby declare the following to be a full, clear, and exact description of the invention, such as will enable 10 others skilled in the art to which it appertains to make and use the same.

This invention relates to new and useful improvements in poultry devices and particularly to brooders.

15 One object of the invention is to provide a device of this character wherein the chicks will be kept warm without the use of artificial heating means, which means throws off gases injurious to the chicks.

20 Another object is to provide a device of this character which is readily adjustable for the purpose of increasing the hover space, as the chicks become larger.

Another object is to provide a device 25 of this character which can be easily and quickly taken apart for cleaning purposes.

Other objects and advantages will be apparent from the following description when taken in connection with the accompanying 30 drawing.

In the drawing:

Figure 1 is an elevation of a brooder made in accordance with the invention.

Figure 2 is a vertical sectional view taken 35 centrally through the brooder on the line 2-2 of Figure 1.

Figure 3 is a horizontal sectional view on the line 3-3 of Figure 1.

40 Referring particularly to the accompanying drawing, A represents the inside or hover section, and B the outside or enclosing section of the brooder, the former being formed from comparatively heavy card-board, while the latter is preferably formed 45 from galvanized metal.

The inside section A includes the circular wall 10, formed from a single length of card-board having the longitudinal series of openings 11 adjacent its upper edge, and an angular notch 12, cut in the center of the lower edge, this latter notch forming the doorway through which the chicks enter the hover chamber. Carried by one end of the wall 10 is a transverse strip 13 beneath 55 which the other end of the wall is arranged

to be disposed, a wire hook 14 being carried by the last named end to secure the ends of the wall against movement from the adjusted position. By means of this adjustment the diameter of the space enclosed by 60 the wall 10 can be made larger or smaller according to the number of chicks, or the size of the chicks. Supported on the upper edge of the wall 10 is a conical roof 15 the same having an opening 16 in its apex, and a longitudinal window 17 in one side near the apex. Formed in the roof 15, in lines radiating from the apex toward the peripheral edge thereof, are the series of openings 15' through which are arranged to be 70 inserted pins 16' which engage outwardly of the circular wall 10 to maintain the roof in position, and to assist in holding the wall. By this arrangement, when the wall 10 is adjusted to increase or diminish its 75 diameter, the pins 16' will be moved into the appropriate openings 15', as will be readily understood.

The floor 18 is preferably formed from a disk of metal, and on this floor the hover 80 chamber is adapted to rest.

Also resting on the floor 18, in concentric spaced relation outward of the wall 10 is the metal wall 19. This wall also has the longitudinal series of ventilating openings 20 85 adjacent its upper edge, and the doorway opening 21 in the center of its lower edge. The ends of the wall 19 are rigidly secured together, to maintain the same diameter, as before explained. Mounted in the doorway 90 21 is a door 22. Extending across the space between the walls 10 and 19, and providing a passageway from the outside of the brooder, to the interior of the brood or hover chamber, is a tunnel-like member 23. This member 23 prevents access to the space between the walls 10 and 19, the air of which is cooler than the air within the hover chamber.

Disposed on the upper edge of the wall 100 19 is a conical roof 24 having an upwardly extending tubular wall in the apex thereof, as shown at 25, said wall 25 being formed with a circular series of ventilating openings 26. Disposed in encircling relation 105 around the wall 25, and also provided with a series of openings 27, arranged to register with the openings 26, is a wall 28, having a dome-shaped cover 29 secured to its upper edge. By means of this wall 28, more 110

or less air may be exhausted through the roof 24 and pass through the opening in the apex of the roof of the brood or hover chamber, while fresh air enters through the 5 openings 11 and 20.

From the foregoing it will be understood that when the chicks are very small, the inner wall 10 is contracted to its smallest diameter, and as the chicks grow, the wall 10 is permitted to expand, making the space enclosed thereby larger, until the wall 10 bears against the outer wall 19, when the chicks are large enough to mingle with the other chickens.

15 What is claimed is:

1. A brooder comprising an inner and an outer housing, each of the housings having a circular wall and a conical roof, the walls and roofs having inlet and outlet 20 openings, the latter openings of the outer roof being regulatable, light entrance means in the said roofs, aligned entrance openings in the walls of the housings, and a tunnel member connecting the entrance openings 25 and extending between the walls of the housings.
2. A brooder comprising an inner and an outer housing, the roof of the outer housing being provided with a tubular wall 30 having openings therein, a movable cover for the tubular wall, said cover being formed with a series of openings positioned to register with those in the tubular wall, the roof of the inner housing being provided with a 35 series of openings, and pins adapted for selective insertion within these openings

and arranged to contact with the wall of the inner housing.

3. A brooder comprising an inner and an outer housing, each of the housings having a circular wall and a conical roof, the roof of the outer housing being provided with an upwardly directed tubular wall, the walls and roofs having inlet and outlet openings, a movable cover for the tubular wall, said cover being provided with a series of openings positioned for selective registry with those in the said tubular wall, entrance openings in the walls of the housings, and a tunnel member connecting the 50 entrance openings and extending therebetween.

4. A brooder comprising an inner and an outer housing, each of the housings having a circular wall and a conical roof, the walls and roofs having inlet and outlet 55 openings, the latter openings of the outer roof being regulatable, supplemental openings formed in the roof of the inner housing, pins adapted for selective insertion 60 within the last mentioned openings and arranged to contact with the outer surface of the wall of the inner housing, entrance openings in the walls of the housings, and a tunnel member connecting the entrance 65 openings and extending therebetween.

In testimony whereof, I affix my signature, in the presence of two witnesses.

MRS. IDA M. YOUNGBERG.

Witnesses:

E. J. LOUTZENHEISER,
G. E. HAMPTON.
